United States Patent Office.

JOHN CAMP, OF OLNEY, ILLINOIS, ASSIGNOR TO HIMSELF AND HENRY MARSHALL, OF SAME PLACE.

Letters Patent No. 82,381, dated September 22, 1868.

IMPROVED LIFTING-JACK.

The Schedule referred to in these Letters Patent and making part of the same.

TO ALL WHOM IT MAY CONCERN:

Be it known that I, JOHN CAMP, of Olney, Richland county, and State of Illinois, have invented a certain new and useful Improvement in Lifting-Jacks; and I do hereby declare the following to be a full, clear, and exact description of the same, reference being had to the accompanying drawing, which forms part of this specification.

The object of this invention is to provide a carriage-jack which answers all the requirements for a four-wheel vehicle, and is cheaply constructed and not liable to get out of order.

The stand consists of a single block of wood, which is slotted to receive the lever-head.

The lever is supported on an arbor, passing transversely through the upper part of the stand, and has a notch upon each side of the head, intended, respectively, to raise the fore and rear axle. In rising, the axle is carried past the centre of oscillation, so that the lever is self-supporting.

In the drawings—

Figure 1 is a side elevation of my improved jack.

Figure 2 is a front elevation of the same.

A is the stand, and B the lever. The latter turns on a pin, C, and has notches or recesses, $b b'$, to receive the axles. The recess b is farther removed from the axis of oscillation than the recess b' , so that when the former is used, the axle will be raised to a higher elevation than when the latter is brought into requisition, thus rendering it available, without any complicated adjustment, for vehicles with four wheels. The central extension, b'' , between the recesses, is made sufficiently broad to bring the axle and the free end of the lever both on one side of a vertical line extending through the arbor, so that the lever is self-sustaining, and requires no special device to hold it in position.

It will be observed that the position of the jack is reversed in using the different recesses.

Having thus explained my invention, I claim as new, and desire to secure by Letters Patent—

The combination of the reversible lever $B b b'$, the stand A, and fulcrum-pin C, relatively arranged to operate in the manner described for the purpose specified.

To the above specification of my improvement in lifting-jacks, I have signed my hand, this 20th day of March, A. D. 1868.
